UNITED STATES PATENT OFFICE

2,364,935

AIR CIRCULATOR

Walter Bandurski, Chicago, Ill.

Application April 25, 1942, Serial No. 440,563

2 Claims. (Cl. 126—110)

This invention relates to improvements in air circulators designed principally for use in dwellings although capable of use elsewhere. One object is to provide an air circulator adapted to circulate warm or cool air about a room or apartment to uniformly heat or ventilate the same.

A further object is to provide an air circulator that is automatic in operation. A further object is to provide an air circulator of few parts that is inexpensive to manufacture, durable in use and that can be readily installed even by persons lacking skill in the art.

A still further object is to provide an air circulator adapted for use in connection with a stove, furnace, or other heating unit and that is operated solely by the exhaust when the unit is in operation thus providing means for effective dissemination of warm air about the apartment served by the unit.

A still further object is to provide an air circulator for installation in an apartment communicating with the atmosphere outside the apartment to automatically ventilate the apartment.

With the foregoing and other objects in view the invention consists in the combination and arrangement of parts to be hereinafter fully described, pointed out in the claims and illustrated in the accompanying drawing which forms a part of this patent and in which—

Fig. 1 is a side view, partly in section and partly broken away, illustrating the application of the air circulator.

Fig. 2 is a view similar to Fig. 1 but omitting the cold air intake and illustrating a slightly modified form of impelling fan structure.

Fig. 3 is a fragmentary view of Fig. 2 illustrating a further modified form of impelling fan structure.

Figs. 4 and 5 are face views of two types of fans employed, and,

Fig. 6 is an enlarged fragmentary sectional view of a shaft.

Like reference characters denote corresponding parts throughout the several views.

The reference numeral 1 denotes a heating unit provided with the conventional pipe 2 leading to the stack 3 and including the elbow 4. Referring now to Fig. 1 the elbow 4 is provided interiorly with a bracket 5 and exteriorly with a bracket 6 in which bearings 7, 8 respectively are carried, said brackets operatively supporting a rotary transmission shaft 9 that passes through one wall of said elbow, said shaft having fast thereupon within said elbow the impelling fan 10 and adjustably thereupon outside said elbow the air disseminating fan 11, preferably larger than the fan 10, said fan 11 being adjustable toward and away from the elbow.

When the heating unit 1 is in operation the smoke and gases therefrom pass through the pipe

to the stack 3 and drive the impelling fan 10 which rotates the shaft 9 and fan 11 which latter member disseminates the hot air rising from the unit 1 about the room or apartment served by said unit. Arranged preferably immediately above the pipe and elbow is a cold air intake pipe 13 that extends through an opening in the structure 14 served by the unit 1 and at its upper end, or somewhat inwardly therefrom, is provided with a screen 15, the inner end of said pipe terminating in spaced relation to one face of the fan 11 so that the air discharged from said pipe will strike against and rotate the fan which will distribute the air about the structure or apartment. The discharge end of the pipe 13 may be closed by a suitable cap (not shown), or otherwise, when not in use.

Referring now to Fig. 2 the pipe 2 carries a shaft 9a extending through its straight portion below the elbow, said shaft being similar to the shaft 9 but having fast thereupon a swash-motion impelling fan 10a. This fan being in a straight portion of the pipe will be contacted with greater force by the smoke and gases passing therethrough than if located in the elbow with the result that a greater speed will be imparted to the circulator.

In Fig. 3 a fan 9b having curved blades is provided, this type of fan having a greater surface presented to the flow of gases through the pipe.

The novel features and the operations of this device will be apparent from the foregoing description. While the device has been shown and the structure described in detail it is obvious that this is not to be considered limited to the exact form disclosed and that changes may be made therein within the scope of what is claimed without departing from the spirit of the invention.

What is claimed is:

1. The combination with a room heater having an inner heating unit, an outer open-top casing, and a smoke pipe leading to a stack; of a rotary transmission shaft in said smoke pipe extending through one wall thereof, a fan fast upon said shaft within said smoke pipe, and a fan upon said shaft outside said smoke pipe positioned to blow air across the top of the heater.
- 45 2. The combination with a room heater having an inner heating unit, an outer open-top casing, a smoke pipe leading to a stack, and an elbow in said smoke pipe disposed at a slightly higher level than and in close proximity to said casing; of a rotary transmission shaft in said elbow extending through the wall thereof in the direction of said casing, a fan fast upon said shaft within said elbow, and a fan fast upon said shaft outside said elbow between the same and said casing to blow air across the top of said casing.

WALTER BANDURSKI.
